BY Francis C. Bowen

ATTORNEY.

UNITED STATES PATENT OFFICE.

JONATHAN BADGER, OF NEW YORK, N. Y.

WINDOW-VENTILATOR.

SPECIFICATION forming part of Letters Patent No. 287,791, dated November 6, 1883.

Application filed February 13, 1883. (No model.)

To all whom it may concern:

Be it known that I, JONATHAN BADGER, a citizen of the United States of America, residing at New York, in the county of New York and State of New York, have invented certain new and useful Improvements in Window-Ventilators, of which the following is a specification, reference being had therein to the accompanying drawings.

10. This invention consists in a ventilator of certain novel construction, which is designed to be applied to the upper part of a window, for the purpose of deflecting or throwing upward the incoming current of fresh air produced when the upper sash is lowered, at the same time permitting the escape of foul air, the latter, as is well known, having a tendency to rise and seek an outlet.

The novel construction of my ventilator is 20 hereinafter fully described, and is illustrated in the accompanying drawings, in which—

Figure 1 represents a vertical cross-section, showing it in position within a window. Fig. 2 is a front view, partly in section.

25. Similar letters of reference indicate corresponding parts.

The letter A designates a frame of a window, containing the usual sashes, B C, and also containing a ventilator which embodies my invention. This ventilator consists of a vertical shield, D, a horizontal ledge, D', attached to one side of the shield, and end pieces, D², attached to both the shield and ledge, each of these parts being preferably made of wood. 30 The longitudinal edge of the ledge D', which is its free edge, is provided with a packing-strip, e, of india-rubber or other similar material. The end pieces, D², have less height than the shield D, thus terminating below the top 40 edge of the shield, and in applying the device to a window the end pieces are secured opposite to the sides of the frame, with their upper edges abutting against the top of the window-opening, and in such a position that the packing-strip e is in the vertical line of the inner

surface of the upper sash, B, while the shield D stands off or away from the frame in an inward direction, it also projecting above the window-opening, as shown in Fig. 1, whereby an opening, s, is created between the shield 50 and the frame. If the upper sash, B, is now lowered a sufficient distance to bring its top bar opposite the ledge D', the packing-strip e impinges against such bar and produces an air-tight joint at that place, while the current 55 of fresh air flowing in through the vacant space above the sash comes in contact with the shield D, and is thereby deflected upward, so that it enters the apartment in that direction through the opening or passage s, as indicated by arrow in Fig. 1. It is obvious that the opening s will also permit the escape of foul air, if any exists in the apartment, while in either case an injurious or undesirable draft is avoided. It will be noticed that the lowering of the upper sash also has the effect of creating an opening between the sashes, through which a current of fresh air is admitted, as indicated in Fig. 1.

It may be remarked that the length of the 70 ventilator corresponds to the width of the window-opening, so that it fits snugly therein, such length being of course varied according to the differences in the sizes of windows.

Having described my invention, what I 75 claim, and desire to secure by Letters Patent, is—

A window-ventilator composed of the shield or deflector D, the ledge D', having its free edge provided with a packing-strip, and the 80 end pieces, D², having a less height than the shield, the whole being adapted for use substantially as described.

In testimony whereof I affix my signature in presence of two witnesses.

JONATHAN BADGER.
